General Motors Corporation, Dayton, Ohio, a
corporation of Delaware

Application November 30, 1939, Serial No. 306,913

10 Claims. (Cl. 257—3)

This application relates to refrigeration and more particularly to an air conditioning system for railway cars and other vehicles.

An object of this invention is to provide an air conditioning system which may be energized from a prime mover of the internal combustion type and which may be automatically controlled by simple and efficient electrical controls.

A further object of this invention is to provide an air conditioning system which may be energized from a prime mover of the internal combustion type which will provide both heating and cooling to an enclosure under a system of controls which provide variable inside temperatures as modified by outside temperatures, and which outside temperature controls are further modified by other outside controls to further modify the inside controls; all of which tends to give the most comfortable inside temperatures in all ranges of outside temperatures.

Further objects and advantages of the present invention will be apparent from the following description, reference being had to the accompanying drawings, wherein a preferred form of the present invention is clearly shown.

In the drawings:

Fig. 1 is a vertical cross section of a portion of a railway car showing the preferred location of some of the elements of the air conditioning system;

Fig. 2 is a cross section taken along the line 2—2 of Fig. 1;

Fig. 3 is a diagrammatic representation of the air conditioning system as applied to a railway car; but the locations of the elements have been altered slightly for a better disclosure of the system;

Fig. 4 is a wiring diagram to disclose the operation of the various electrical controls for the system;

Figs. 5 and 6 combined show the same wiring diagram which is shown in Fig. 4 on an enlarged scale and includes means for indicating which switches are operated by each solenoid.

THE REFRIGERATION SYSTEM

The refrigeration system preferably includes a compressor 100, a condenser 101, an evaporator 102 in refrigerant flow relationship. The evaporator may be provided with an expansion valve 103 tending to open whenever the refrigerant pressure in the evaporator falls below a predetermined limit. This valve 103 is modified by a thermostatic bulb 104 placed near the outlet of the evaporator which tends to throttle or close

the valve 103 whenever the proper refrigerating effect reaches the bulb 104.

A liquid refrigerant solenoid control valve 132 is placed in the liquid refrigerant line 132a as a primary control of the liquid refrigerant flowing to the evaporator 102 through the expansion valve 103. The valve 132 is opened and closed by temperature responsive controls positioned within the car to cycle the refrigeration effect of evaporator 102, the operation of which will be hereinafter more fully explained. When the liquid refrigerant line 132a is closed by the valve 132 to stop the flow of refrigerant to the evaporator 102, a by-pass valve 147 automatically opens to permit the flow of a small amount of refrigerant, through the by-pass line 147a, to the compressor. The valve 147 is of the usual automatic expansion type which is set to open when the suction pressure falls to some relatively low predetermined pressure and will open only when valve 132 is closed. This by-pass line 147a permits the compressor 100 to be operated continuously, by the internal combustion engine, whether refrigeration is needed or not, without overheating the liquid refrigerant expanding through the by-pass absorbing the heat of friction of the compressor.

The refrigerant is compressed at the compressor 100, condensed at the condenser 101, expanded at the evaporator 102 and returned to the compressor 100 in a cycle well known in the air conditioning art.

The condenser 101 is provided with a fan 122 driven by an electric motor 123.

The air to be conditioned within the car is circulated by a blower 124 driven by a blower motor 125. Air is drawn from the interior of the car 126 through the recirculating air inlet 127 and from the exterior of the car through the fresh air inlet 128. The air is then discharged into the interior of the car through the outlet or distributing means 129.

THE POWER SOURCE

The power source for the air conditioning system may be an engine of the internal combustion type, such as a Diesel, kerosene or gasoline internal combustion engine. The specific disclosure in this application is for a Diesel engine; although it is to be understood that the system can be varied to use a kerosene or gasoline engine. The Diesel engine is indicated at 105. It is provided with the usual water cooling jacket connected to a water cooling radiator 106. While the cooling water may be arranged to circulate

by convection, it is preferred to provide a water pump driven by the engine 105, which causes water to circulate between the water jacket of the engine and the radiator 106. In addition, the water may be circulated to a reheat coil 107 which provides heat radiation surface for the hot water from the engine during certain periods of operation of the system, the function of which will be hereinafter more fully explained. The engine may be provided with a starter 108, which may be an electric motor geared by the usual starter mechanism to the flywheel 109 in such a manner that the starter 108 is connected to the flywheel when energized, and is disconnected after the engine attains a proper speed. The engine is further provided with a fan 110 for circulating air through the radiator 106.

The engine is also provided with other well known appurtenances such as a fuel tank 111 connected by a line 112 leading to a fuel injector and throttle control mechanism upon the engine, as is well known in Diesel practice. The fuel line 112 is provided with a solenoid valve 113 for controlling the flow of fuel to the engine. An automatic throttle 114 is provided on the engine and is placed under the control of a centrifugal governor for maintaining the proper speed of the engine under all load conditions. The engine is provided with the usual fuel injecting pump mechanism for feeding the fuel to the engine under control of the automatic throttle. An auxiliary pump 115 is provided for injecting fuel into the wind box of the engine for starting the engine under unusually cold conditions. The pump 115 pumps fuel from the line 112 into the wind box 116 where the fuel is ignited by a spark plug 117. Ignition of the fuel in the wind box heats the air entering the engine and thus insures ignition of the fuel charges injected into the cylinders.

The wind box 116 is also provided with a control 118 responsive to the pressure of the air in the box 116. The control 118 includes a switch which, when the air pressure has been built up by the speed of the engine to the proper degree, disconnects the starter and connects the clutch 119 to cause the engine 105 to drive a generator 120, and the compressor 100. The compressor 100 is driven from the generator through the medium of belts 121. The pressure of the air in the wind box 116 is created by an air pump (not shown) driven by the engine in such a manner that the pressure in the box 116 is proportional to the speed of the engine.

THE VALVES, THERMOSTATS, ETC.

Valves, thermostats, etc., are provided in the system for the proper functioning of the same, but before describing the functions of these various elements, the general construction of the elements is now described.

Mercury thermostats or thermometers are provided which open and close an electric circuit by means of a mercury column rising and falling within a sealed tube and thus making contact with electric terminals extending through the walls of the tube into the path of the column of mercury. These mercury thermometers are indicated at 79, 75, 72, 78, 74, 71, 70, 80, 90, 10, 60, 72A, 72B, 71A and 60A.

Solenoid valves are used which open or close when the solenoid of the valve is energized. Such valves are indicated at 130, 131, 132, 133 and 134. Valves 131, 132, 133 and 134 are opened when the solenoid is energized. Valve 130 is closed when the solenoid is energized.

Heat-operated valves are used. These valves are heated by electric resistances, and when so heated, are closed. These valves are indicated at 135, 136, 137 and 138.

Electric relays are provided for making and breaking electric circuit, and include a solenoid and movable contact or contacts. In Fig. 4, the solenoid portion of any relay is indicated by a winding symbol. The movable contact or contacts are shown by horizontal lines adjacent two small circles. The two small circles indicate the stationary contact or contacts which cooperate with the movable contact or contacts to open or close an electrical circuit. A designating letter or letters indicate each of the electric solenoid windings. Immediately following the letter or letters, a numeral or numerals are placed to designate the movable contact or contacts operated by such solenoid. The designating letter for each of the relay solenoids, together with a numeral, will identify the contact or contacts operated by that particular relay solenoid. Thus, the designating character of the solenoid indicates the number of contacts operated thereby, while the designating letter plus a numeral indicates each of the contacts operated thereby. Each of the contacts is correctly identified. For example, the symbol "B"—1—2—3 indicates a solenoid which operates three contacts. These contacts are designated respectively as B—1; B—2; and B—3. The contacts B—1 and B—2 are opened when the solenoid is energized, while the contact B—3 is closed when the solenoid is energized.

Further, each of the movable contacts of the relays is so positioned with respect to its stationary contacts that upon deenergization of the relay coil, the movable contact will fall to open or close electric circuit through the stationary contacts according to whether the movable contact is positioned above or below the stationary contacts. Energization of the relay coil moves the movable contacts upwardly with like result.

Resistances 139 are inserted in the circuits to reduce the current value and balance the potential across the contacts of the mercury tubes to prevent arcing at that point. These resistances 139 are used when the controlling mercury tube is shunted across the solenoid of the relay. The resistances 140 are for a similar purpose, but are used where the relay solenoid is in series with the mercury tubes. These resistances 140 provide surge current protection to the mercury tubes in the series circuit, tending to maintain a constant voltage through the mercury tubes when contact is made or broken; the resistances absorbing the current surge to prevent arcing or boiling of the mercury.

As shown in Figs. 3 and 4, the reference numeral 200 designates those thermostats which are located in the return air duct and which therefore respond to the temperature of the air inside the enclosure. Reference character 202 designates those thermostats which are located in the fresh air duct and which therefore respond to the temperature of the outside air. A third group of thermostats, located adjacent the floor of the conditioned space, has been designated by the reference numeral 204.

To describe a typical operation of an electrical control, reference is made to the upper part of Fig. 4. For example, when the temperature adjacent the tube 72 is rising, and reaches a temperature of 72° F., the contacts of tube 72 will be bridged, providing electric circuit therethrough. If the contact A—2 is in a lower position an elec-

trical circuit is made across the battery through the tube 72 which shunts the resistance RH. When the resistance is thus deenergized, the contact RH-1 opens its circuit. If, for any reason, the contact A-2 is in its upper position, thus disabling mercury tube 72, and if contacts B-2, D-2 should be in their lower positions, when the temperature reaches 75° F., the tube 75 makes a circuit across the battery and shunts the solenoid RH with a similar result. Likewise, if tubes 72 and 75 should be disabled and contacts C-2 should be closed, tube 79 can control the solenoid RH and its contact by making and breaking a circuit across the battery.

THE AIR CONDITIONING SYSTEM

The operation of the air conditioning system is regulated by means of temperature responsive controls positioned within the car, which controls are modified in their operation by the temperature outside the car. When the outside temperature is sufficiently high to require a reduction of the temperature of the air inside the car below the temperature outside the car, the air conditioning system is so regulated as to provide a gradual increase of inside temperatures when the outside temperature increases; the inside temperature, however, increases at a much slower rate than the outside temperature. Also, when the outside temperature falls sufficiently low, the air conditioning system will supply heat to the air either from the water system of the internal combustion engine or the usual steam supply on the train, or both. On cold days, higher inside temperatures are produced than on mild days. At all times, however, both refrigeration and heating systems may be rendered effective by the inside temperature controls, regardless of the temperature outside the car. For example, if the car should become too cool on a warm day, heat will be supplied alone or at the same time refrigeration is being supplied by the air conditioning system to raise the car temperature, or vice versa if the car temperature should become too warm on a cold day, refrigeration will be supplied alone or at the same time heat is being supplied by the air conditioning system to reduce the temperature of the air within the car. Thus, it can be seen that the system is not merely a heating or cooling system, but is a system for regulating the temperature inside the car at a constant level; the temperature level being selected according to the conditions prevailing outside the car. Mercury tubes are placed in a position to be responsive to the temperature inside the car for certain controls, and other mercury tubes are placed in a position to be responsive to temperatures outside the car to modulate the inside controls.

On the warmest days, the air is cooled by the evaporator 102 alone. When the outside temperature falls to a less warm zone, evaporator 102 is operated, but its effect is counter-balanced in part by the reheat coil 107. Then, as the outside temperature falls into a cold zone, the air is heated by reheat coil 107 alone, or supplemented by steam coil 141, it being understood that under all conditions, the effect of heat or refrigeration is always available to temper the effect of the other.

The reheat

Reheat is generally obtained from the water system of the engine 105. The reheat coil 107 and radiator 106 are placed in parallel flow rela-

tionship with each other and in series with the jacket of the engine. The valves 130 and 131 are used to control the flow of hot water through one or the other of these coils. When necessary, as when the refrigeration system is being operated by the generator 120 acting as a motor, reheat can be produced by the supplementary steam coil 141 with the same result as reheat obtained from coil 107.

10 OPERATION UNDER DIFFERENT OUTSIDE CONDITIONS

The electrical system of Fig. 4 is shown under conditions where the outside temperature is slightly below 70° F., but above 60° F. A master switch M is provided, which is closed whenever it is desired to place the system in readiness for operation, and which may be opened to disable all of the electrical system except the necessary steam valves for the floor heat under yard conditions. The engine is idle, but the system is in readiness for operation since the master switch M is closed. The operation of the system under various outside conditions will now be described.

Operation at 90° F. outside temperature

25 When the outside temperature is 90° F., or above, refrigeration is produced in evaporator 102 and, if necessary, reheat is provided. The inside controls 79 and 78 are placed in command of the air conditioning system and tend to maintain the temperature inside the car between 79° F. and 78° F.

30 The above result is produced because the mercury columns in mercury tubes 70, 80 and 90 are all in contacting position. The closing of the circuit through 90 disables the controls 70 and 80 because the deenergization of solenoid C opens contacts C-3 and C-4. In addition, the contacts C-1 and C-2 are closed to place mercury tubes 71 and 78 in command of relays RH and LL. The controls 71, 72, 74 and 75 are disabled because of the disabling of controls 70 and 80 which, in turn, causes energization of solenoids A and B, with the consequent opening of contacts A-1, A-2, B-1, B-2 and B-3. Contacts C-5 and C-6 are also open at this time to break circuit through mercury tubes 74, 75.

35 With the controls set as above, and with the engine and the refrigeration system operating (the same having been started as hereinafter described), the full refrigeration capacity of the system is placed in operation on the air being circulated by the blower 124. If the temperature in the car is above 79° F., reheat is prevented because relay RH is deenergized, opening contact RH-1 and deenergizing valves 130 and 131. Valve 131 is closed when deenergized, thereby preventing circulation of hot water through reheat coil 107. If the temperature inside the car should continue to fall and reach a point between 78° F. and 79° F., relay RH is energized, thus closing contacts RH-1 and energizing solenoid valves 130 and 131. The energization of valves 130 and 131 opens valve 131 and closes valve 130 thus shifting the flow of hot water from the engine to the reheat coil 107 to produce reheat in coil 107, thus tending to neutralize, to some extent, the refrigerating effect of the evaporator 102.

40 45 50 55 60 65 70 75 78 If the temperature inside the car should continue to fall, and fall below 78° F., refrigeration would be stopped entirely. Electric circuit through mercury tube 78 will be broken, thus deenergizing solenoid relay LL which, in turn, opens contact LL-1. The opening of contacts

LL—1 deenergizes and closed liquid refrigerant valve 132 and stops the operation of condenser fan 123, thus stopping refrigeration. Heat alone will now be supplied to the circulating air in the car until the temperature again rises above 78° F.

Operation when outside temperature is between 80° F. and 90° F.

When the outside temperature is at 80° F., but below 90° F., refrigeration is produced, with or without necessary reheat; but the air conditioning system is placed under the control of inside mercury tubes 74 and 75, with a consequent tendency to maintain the temperatures inside the car between 74° F. and 75° F.

The above results are produced because as the outside temperature falls below 90° F., circuit will be opened through mercury tube 90, thereby energizing relay C, closing contacts C—3, C—4, C—5, C—6 and opening contacts C—1 and C—2. This places mercury tube 80 in control. The closing of the circuit through mercury tube 80 deenergizes relay B, with the consequent closing of contacts B—1 and B—2 and opening B—3. The opening of contacts B—3 disables control 70.

If the temperature inside the car is above 75° F., the circuit through mercury tube 75 is closed, with the consequent prevention of reheat by the deenergization of relay RH and consequent closing of valve 131. If the temperature inside the car should then fall between 74° F. and 75° F., refrigeration with reheat is produced by the opening of the circuit through tube 75 and the maintenance of the circuit through tube 74 in the closed position. If the temperature inside the car should continue to fall below 74° F., refrigeration is stopped by the opening of the circuit through tube 74, with the consequent closing of liquid refrigerant valve 132 and the stopping of condenser fan 123.

Operation when outside temperature is between 70° F. and 80° F.

When the outside temperature is at or above 70° F., but below 80° F., refrigeration is produced with or without reheat with a tendency to maintain inside temperatures between 71° F. and 72° F. under the control of tubes 71 and 72.

The above results are obtained because the circuit through tube 70 is closed, and the circuits through tubes 80 and 90 are opened. The opening of the circuits through tubes 80 and 90 places the tube 70 circuit in control of the air conditioning system. As the outside temperature fell and opened the circuits through tubes 80 and 90, the contacts B—3 and C—3 were closed and the relay A was deenergized, with the consequent placing of contacts A—1 and A—2 in the deenergized position. In addition, the opening of the circuits tubes 80 and 90 disabled controls 74, 75, 78 and 79.

If the temperature inside the car is above 72° F., refrigeration is produced with or without reheat under the control of controls 71 and 72. As both of these circuits are closed, refrigeration is produced without reheat. As the refrigeration thus produced tends to lower the temperature in the car until it is below 72° F. and above 71° F., refrigeration with reheat is produced by the consequent opening of valve 131 and closing of valve 130. If the temperature should continue to fall and fall below 71° F., refrigeration is stopped in the same manner hereinbefore described.

Operation when outside temperature is between 70° F. and 60° F.

When the outside temperature is below 70° F., but above 60° F., the air conditioning system is placed under the control of inside thermostats 74, 75, and the reheat coil 107 and evaporator 102 are controlled in a manner tending to maintain the inside temperature between 74° F. and 75° F.

The above results are obtained due to the opening of the circuits through tubes 70, 80 and 90. The opening of the circuit through 70 energizes relay A, with the consequent raising of contacts A—1 and A—2 to a position where they close upon the circuits of thermostat tubes 74, 75, thereby placing them in control. Thus, as the outside temperature falls below 70° F., the temperature range inside the car is raised from 71° F.—72° F. range to 74° F.—75° F. range to compensate for the lower outside temperature.

If the temperature inside the car is above 75° F., as previously described, refrigeration alone is produced; if between 74° F. and 75° F., refrigeration with reheat is produced; while if below 74° F., reheat alone is produced.

Operation when outside temperature is between 60° F. and 10° F.

When the outside temperature falls below 60° F., but is still above 10° F., the evaporator 102 and reheat coil 107 continue under the control of inside thermostats 74, 75; but in addition, supplementary heat may be provided at the coil 141 and the floor heat coils 142, 143 and 144.

Tube 60 is responsive to outside temperatures, while tube 72A is responsive to floor temperatures in the car. As long as the outside temperature is above 60° F. and the car floor temperature is above 72° F., supplementary heat is not required. However, when both outside and inside temperatures fall below the above respective values, supplementary heat will be required. The tubes 60 and 72A are placed in parallel, electrically, so that the conditions of both must be met before supplementary heat is available.

When the outside temperature falls below 60° F. and the floor temperature falls below 72° F., the supplementary steam heat, from the coils 142, 143, 144, is placed under the control, in the first instance, of floor thermostat 72A, which, in turn, places the supplementary steam heat under the control of floor thermostats 72B, 71A, and 60A.

If the floor temperature is below 72° F., but above 71° F., steam is provided to coil 142 only under control of tube 72B and valve 136.

If the floor temperature falls below 71° F., steam is provided to the floor coil 143 under the control of tube 71A and valve 137.

Coil 141 is under the further control of a thermostatic valve 145, which will not open until the temperature of the air passing over the supplementary thermostatic control bulb 146 is below a selected temperature. As long as the temperature of the air passing over the reheat coil 107 is sufficiently high, the supplementary steam coil 141 will not function, the valve 135 being closed. If the reheat coil supplies insufficient heat to the car, then bulb 146 will open valve 135 and permit steam to flow to coil 141.

The above addition of supplementary steam is accomplished because the circuit through tube 60 is opened by the outside temperature being below 60° F., while the circuit through tube 72A is opened because the floor temperature of the car is below 72° F. This condition energizes relay E, with the consequent opening of the contacts E—1,

E-2 and E-3. Contact E-1 cuts off current to valve 135. This valve opens when its heating coil ceases to be energized, due to the opening of the electric circuit therethrough, thus providing steam to the coil 141 as previously described. The opening of contact E-2 places thermostat 72B in control of the valve 136. The opening of the circuit through 72B energizes relay F, with the consequent opening of contact F-1 and deenergization of the heating element in valve 136. This deenergization of valve 136 permits the valve to open and provide steam to coil 142. The opening of contact E-3 places valve 137 under the control of floor thermostat 71A. If the floor temperature should fall below 71° F., the opening of circuit through thermostat 71 energizes relay K, with the consequent opening of contacts K-1, deenergization of valve 137, opening of valve 137 and the supply of steam to coil 143.

From the above, it is to be seen that, when the outside temperature is below 70° F., but above 60° F., the general inside temperature of the car tends to be raised to a range between 74° F. and 75° F. and the floor temperature tends to be maintained between 71° F. and 72° F., thus producing comfort conditions at all levels in the car.

Operation when outside temperature is below 10° F.

When the outside temperature falls below 10° F., the control of the air conditioning system is placed under the control of inside thermostats 78 and 79, with the same floor heat control previously described.

The above results are produced by the opening of circuit through tube 10, with the consequent energization of relay D which, in turn, opens contacts D-1, D-2 and closes contacts D-3. The closing of contacts D-3 closes circuit in the same manner as if mercury tube 90 were closed, with the consequent deenergization of relay C, and the consequent placing of contacts C-1 through C-6 in the deenergized position. The circuits through tubes 70 and 80 are open due to the low outside prevailing temperature. With circuit through tube 90 closed, thermostats 78 and 79 are in control of the refrigerating system, if it is being operated, and the reheat coil 101, while the control of the supplementary steam continues exactly in the same manner as has been previously described.

It is to be understood that, ordinarily, the refrigerating system will have stopped long before any outside temperatures reach 10° F. or below; but on certain north and south railroads, cars frequently operate between extreme outside temperature conditions and, therefore, it may be convenient to continue operation of the refrigerating system at all times.

OPERATION WHEN CAR IS IN YARD

When the car is idle and is placed in the yard, or under similar conditions, it is generally desirable to stop the operation of the Diesel engine, and provide for a certain amount of floor heat. The floor heat will be sufficient to prevent freezing of the equipment on the car. This is accomplished by placing the engine control 148 in the "off" position. The control 148 is mechanically interlocked with switches 149 and 150 in such a manner that switches 149 and 150 are closed when 148 is in the "off" position, but are opened when the control 148 is either on the Diesel or motor positions. When the switches 149 and 150 are closed, the valves 136 and 137 are energized,

thus closing them and preventing a supply of steam to coils 142 and 143.

If the floor temperature should fall below 60° F., the control 60A opens and energizes relay L, which, in turn, opens contacts L-1, with the consequent deenergization and opening of solenoid valve 138. The opening of valve 138 supplies steam to floor coil 144, which is just large enough to heat the car to prevent freezing of the equipment.

STARTING CONTROL OF THE DIESEL ENGINE

The Diesel engine is controlled and started by moving the control 148 to the "Diesel" position. While the engine is in idle condition, contacts 151 are open, thus deenergizing relay H and permitting contacts H-1 to be closed. This produces a circuit through the starter 108 and cranks the engine. At this time, the fuel valve 134 is energized and opened to supply fuel to the engine. If the temperature of the engine is above 40° F., the engine will start upon being cranked. When sufficient speed has been attained, the pressure in the wind box 116 rises to operate control 118 and close contacts 151. The closing of contacts 151 energizes relay H and moves contacts H-1 to the upper position, thus opening the circuit to the starter and simultaneously closing the circuit to solenoid valve 133. Solenoid valve 133 supplies air to the pneumatic clutch 119 and connects the engine 105 to the generator 120.

At this time, the relay G being unenergized, contacts G-1 and G-2 are in their lower position. The generator 120 has its field winding 152 energized through G-1 and the carbon pile 153 of the voltage and current regulator 154. A series coil 155 and a shunt coil 156 control the contact 157 in the well known manner, so that when the voltage across the terminals of the generator is at the proper value in relation to the battery voltage, contacts 157 are closed; but are maintained open if the generator voltage is not sufficiently high. The current and voltage regulator 154 includes a current coil 158 and a voltage coil 159, which tend to increase the resistance of carbon pile 153 when either the current or voltage exceeds their respective safe limits.

A manually adjustable resistance R is provided for varying the effect of coil 158 to regulate the output of the generator, as is well understood.

If the temperature of the engine should be below 40° F., a supplementary air heating means is provided for the engine, to insure starting thereof. For this purpose, a thermostat 160 conveniently may be placed in the water jacket, and when this is below 40° F., it closes contacts 161. When the control 148 was moved to the "Diesel" position, relay O was energized, with the consequent closing of contacts O-1. Contacts O-1 and 161 being closed, and contacts 162 being normally closed under the tension of spring 163, current is provided through the vibrator 164 to the transformer 165 and spark plug 117 to produce ignition in the wind box 116. At the same time, the supplementary fuel pump 115 is energized and supplies fuel simultaneously to the wind box 116. The fuel is ignited by the spark plug and heats the air before the same is supplied to the cylinders of the engine, thus insuring starting of the engine under cold conditions.

A suitable timing mechanism is provided for cutting off the supplementary air heating means after the proper time interval. Conveniently,

this may include a thermostatic resistance 166 which closes upon contact 167 after the proper interval of time. The closing of this circuit energizes holding relay 168, which maintains contacts 162 open as long as this circuit is maintained energized by contacts O-1 or 161, thus preventing further supply of fuel to the wind box 116. After the engine has been in operation a short time, the water temperature rises above 40° F., at which time contacts 161 are opened, thus deenergizing the supplementary fuel circuit for the remainder of the operating time of the engine.

OPERATION OF THE D. C. MOTOR

It is necessary for certain railroads to stop operation of the Diesel engine, yet at the same time it is desirable to provide air conditioning for the car. Such conditions occur at terminals where the fumes of the internal combustion engine might be harmful. Under these conditions, the compressor 100 may be driven by the generator 120 acting as a motor, and reheat, if necessary, will be supplied by the steam coil 141.

To accomplish this motoring operation, the control 148 is moved to the "motor" position. When so moved, the control 148 energizes relay G, thus moving contacts G-1, G-2, G-3 to the energized position. The opening of the contacts G-1 and G-2 changes the field winding 152 of the generator to a motoring winding, since contact G-1 moves to the upper position where it places winding 152 in series with the supplementary resistance 169. The closing of contacts G-3 opens solenoid valve 131 to permit steam to be available to coil 141 under control of valve 145 and bulb 146. The by-pass through valve 131 may, however, be extended to include bypassing of valve 145 and this arrangement will permit coil 141 to act as a reheat coil in the same manner as coil 107. Under these conditions, valve 131 is energized at the same time that reheat coil 107 previously was energized when the system was operating under Diesel power. When the control 148 was moved to the "motor" position, the motor starter relay 170 was energized to move the contact 171, under the control of a time delay device 172, to sequentially close the contacts 173 to gradually throw out resistance 174 until normal motoring operation is obtained.

During motoring operation, the refrigeration system and the auxiliary steam coil 141, now acting as a reheat coil, are under control of the same set of temperature responsive thermostat tubes as when on Diesel operation. Refrigeration alone, refrigeration with reheat, or heating alone may be obtained in the same manner as before.

SUMMARY OF OPERATION OF SYSTEM

The operation of the air conditioning system is regulated by means of temperature responsive controls positioned within the car, which controls are modified in their operation by the temperature outside the car. When the outside temperature is sufficiently high to require a reduction of the temperature of the air inside the car below the temperature outside the car, the air conditioning system is so regulated as to provide a gradual increase of inside temperatures when the outside temperature increases; the inside temperature, however, increases at a much slower rate than the outside temperature. Also, when the outside temperature falls suf-

ficiently low, the air conditioning system will supply heat to the air either from the water system of the internal combustion engine or the usual steam supply on the train, or both. On cold days, higher inside temperatures are produced than on mild days. At all times, however, both refrigeration and heating systems may be rendered effective by the inside temperature controls, regardless of the temperature outside the car.

On the warmest days, the air is cooled by the evaporator 102 alone. When the outside temperature falls to a less warm zone, evaporator 102 is operated, but its effect is counter-balanced in part by the reheat coil 107. Then, as the outside temperature falls into a cold zone, the air is heated by reheat coil 107 alone, or supplemented by steam coil 141, it being understood that under all conditions, the effect of heat or refrigeration is always available to temper the effect of the other.

When the outside temperature is 90° F., or above, refrigeration is produced in evaporator 102 and, if necessary, reheat is provided. The inside controls 79 and 78 are placed in command of the air conditioning system and tend to maintain the temperature inside the car between 79° F. and 78° F.

When the outside temperature is at 80° F., but below 90° F., refrigeration is produced, with or without necessary reheat; but the air conditioning system is placed under the control of inside mercury tubes 74 and 75, with a consequent tendency to maintain the temperatures inside the car between 74° F. and 75° F.

When the outside temperature is at or above 70° F., but below 80° F., refrigeration is produced with or without reheat with a tendency to maintain inside temperatures between 71° F.

and 72° F. under the control of tubes 71 and 72.

When the outside temperature is below 70° F., but above 60° F., the air conditioning system is placed under the control of inside thermostats 74, 75, and the reheat coil 107 and evaporator

102 are controlled in a manner tending to maintain the inside temperature between 74° F. and 75° F.

When the outside temperature falls below 60° F., but is still above 10° F., the evaporator 102 and reheat coil 107 continue under the control of inside thermostats 74, 75; but in addition, supplementary heat may be provided at the coil 141 and the floor heat coils 142, 143 and 144.

When the outside temperature falls below 60° F. and the floor temperature falls below 72° F., the supplementary steam heat, from the coils 142, 143, 144, is placed under the control, in the first instance, of floor thermostat 72A, which, in turn, places the supplementary steam heat under the control of floor thermostats 72B, 71A, and 60A.

When the outside temperature falls below 10° F., the control of the air conditioning system is placed under the control of inside thermostats 78 and 79, with the same floor heat control previously described.

When the car is idle and is placed in the yard, or under similar conditions, it is generally desirable to stop the operation of the Diesel engine, and provide for a certain amount of floor heat.

If the floor temperature should fall below 60° F., the control 60A opens and energizes relay L, which, in turn, opens contacts L-1, with the

consequent deenergization and opening of sole-noid valve 138. The opening of valve 138 supplies steam to floor coil 144, which is just large enough to heat the car to prevent freezing of the equipment.

It is to be understood that the temperatures used throughout the specification are for purposes of illustration only, and that temperatures other than those selected can be used without varying the scope of the invention.

While the form of embodiment of the invention herein disclosed constitutes a preferred form, it is to be understood that other forms might be adopted, all coming within the scope of the claims which follow.

What is claimed is as follows:

1. Air conditioning apparatus for a vehicle comprising in combination, a refrigerating system having an evaporator, a compressor and a condenser connected in refrigerant flow relationship, an internal combustion engine for operating said compressor, means using waste heat from said engine for reheating air cooled by said evaporator, temperature responsive means for controlling the flow of refrigerant to said evaporator, and means for flowing liquid refrigerant in thermal exchange with a portion of said compressor when said temperature responsive means indicates that no cooling of the air for said vehicle is required.

2. In combination, a heating system comprising an engine and heat dissipating means associated therewith, a cooling system comprising an evaporator, compressor and condenser connected in refrigerant flow relationship, means for circulating air within an enclosure in heat transfer relationship with said heating and cooling means, a generator driven by said engine, electrically operated thermostatic regulating means energized from said generator and adapted to maintain a selected temperature within the enclosure, said regulating means comprising a plurality of thermostats selectively operative to control the flow of heat from the engine to the enclosure, and a plurality of thermostats selectively operative to control the refrigeration system, said thermostats providing a plurality of temperature ranges in which heating and cooling can be obtained, and means outside the enclosure comprising a plurality of thermostats for selectively determining which of the temperature ranges of the inside thermostats shall be active according to prevailing outside temperatures.

3. In combination, a heating system comprising an engine and heat dissipating means associated therewith, a cooling system comprising an evaporator, compressor and condenser connected in refrigerant flow relationship, means for circulating air within an enclosure in heat transfer relationship with said heating and cooling means, electrically operated thermostatic regulating means adapted to maintain a selected temperature within the enclosure, comprising a plurality of thermostats selectively operative to control the flow of heat from the engine to the enclosure, and a plurality of thermostats selectively operative to control the refrigeration system, said thermostats overlapping in their control functions to provide a plurality of temperature ranges in which either heating or cooling or cooling plus heating can be obtained, and means outside the enclosure comprising a plurality of thermostats for selectively determining which of the temperature ranges of

4. Air conditioning apparatus comprising in combination, a heating system and a cooling system for either simultaneously or independently conditioning air for said enclosure, means to supply supplementary heat to said enclosure to augment the capacity of said heating system, means responsive to temperature conditions within said enclosure for turning on said heating system while said cooling system is in operation, means responsive to temperature conditions within said enclosure controlling said cooling system, means responsive to temperature conditions outside said enclosure for modifying the effective operating temperature range of said heating and cooling systems, apparatus responsive jointly to temperature conditions inside and outside said enclosure controlling said supplementary heat so as to turn on said supplementary heat when both the inside temperature and the outside temperature indicate the necessity for supplementary heat and for turning off the supplementary heat when either the outside temperature or the inside temperature indicates that no supplementary heat is required.

5. Air conditioning apparatus for a vehicle comprising in combination, a refrigerating system having an evaporator, a compressor and a condenser connected in refrigerant flow relationship, an internal combustion engine for operating said compressor, means using waste heat from said engine for reheating air cooled by said evaporator, temperature responsive means for controlling the flow of refrigerant to said evaporator, and means for flowing liquid refrigerant in thermal exchange with a portion of said compressor when said temperature responsive means indicates that no cooling of the air for said vehicle is required, said means for flowing liquid refrigerant in thermal exchange with a portion of said compressor comprising means for bypassing said evaporator.

6. Air conditioning apparatus comprising in combination, a refrigerating system having an evaporator, a compressor and a condenser connected in refrigerant flow relationship, an internal combustion engine for operating said compressor when cooling of the air is required and at times when no cooling of the air is required, valve means for preventing the flow of refrigerant to said evaporator, and means for flowing liquid refrigerant in thermal exchange with a portion of said compressor when said valve means prevents the flow of refrigerant to said evaporator.

7. In combination, a heating system comprising heat dissipating means, a cooling system comprising an evaporator, compressor and condenser connected in refrigerant flow relationship, means for circulating air for an enclosure in heat transfer relationship with said heating

and cooling means, thermostatic regulating means adapted to maintain a selected temperature within the enclosure, comprising thermostatic means selectively operative to control the flow of heat from the heating system to the enclosure, and thermostatic means selectively operative to control the refrigeration system, said thermostatic meanslapping in their control functions to provide a plurality of temperature ranges in which either heating or cooling or cooling plus heating can be obtained, and thermostatic means outside the enclosure for selectively determining which of the temperature ranges of the inside thermostats shall be active according to prevailing outside temperatures.

9. In combination, a heating system comprising heat dissipating means, a cooling system comprising an evaporator, compressor and condenser connected in refrigerant flow relationship, means for circulating air for an enclosure in heat transfer relationship with said heating and cooling means, thermostatic regulating means adapted to maintain a selected temperature within the enclosure, comprising a plurality of thermostats selectively operative to control the flow of heat from the heating system to the enclosure, and a plurality of thermostats selectively operative to control the refrigeration system, said thermostats overlapping in their control functions to provide a plurality of temperature ranges in

which either heating or cooling or cooling plus heating can be obtained, and means outside the enclosure for selectively determining which of the temperature ranges of the inside thermostats shall be active according to prevailing outside temperatures.

- 5 10. In combination, a heating system comprising an engine and heat dissipating means associated therewith, a cooling system comprising an evaporator, compressor and condenser connected in refrigerant flow relationship, means for circulating air within an enclosure in heat transfer relationship with said heating and cooling means, electrically operated thermostatic regulating means adapted to maintain a selected temperature within the enclosure, comprising thermostatic means selectively operative to control the flow of heat from the engine to the enclosure, and thermostatic means selectively operative to control the refrigeration system, said thermostatic means overlapping in their control functions to provide a plurality of temperature ranges in which either heating or cooling or cooling plus heating can be obtained and thermostatic means outside the enclosure comprising a plurality of thermostats for selectively determining which of the temperature ranges of the inside thermostats shall be active according to prevailing outside temperatures.
